UNITED STATES PATENT OFFICE.

ELIZABETH ZIEGFELD, OF ROCHESTER, NEW YORK.

COMBINATION CAP AND SUNBONNET.

1,082,144.

Specification of Letters Patent. Patented Dec. 23, 1913.

Application filed April 14, 1913. Serial No. 761,121.

To all whom it may concern:

Be it known that I, ELIZABETH ZIEGFELD, citizen of the United States, residing at Rochester, in the county of Monroe and 5 State of New York, have invented certain new and useful Improvements in Combination Caps and Sunbonnets, of which the following is a specification, reference being had to the accompanying drawings.

10 This invention comprehends certain new and useful improvements in head gear and has for a primary object to provide a combination cap and sun bonnet.

Another object of the invention is to provide 15 a head gear which may be readily converted into a cap or sun bonnet, as desired.

A further object is to provide a combination cap and sun bonnet which may be readily converted into either of these forms 20 of head gear by reversing the position of the double flaps secured to the lower edge of the crown.

A further object is to generally improve 25 and simplify the construction of devices of this character and increase the efficiency of the same while at the same time the cost of the device will be reduced.

With the above and other objects in view, this invention consists in the novel features 30 of construction, combination and arrangement of parts to be hereinafter more fully described, claimed and illustrated in the accompanying drawings, in which—

Figure 1, is a side elevational view of my 35 device in use as a sun bonnet. Fig. 2, is a perspective view of the device in position upon a head in use as a cap, the flaps being folded back. Fig. 3, is an enlarged detail 40 transverse vertical sectional view through my combination cap and sun bonnet. Fig. 4, is a fragmentary perspective view, partly 45 in section, showing the manner in which the double flap member is secured to the edge of the crown. Fig. 5, is a view similar to Fig. 4, showing the manner in which the braid is secured in the upper edge of the double flap member.

Referring more specifically to the drawings in which similar reference characters 50 designate corresponding parts throughout the several views, 1 designates the crown of the device, which crown is gathered around its edge, as shown at 2. It will be seen that the crown which is formed of one 55 piece of material having a circular edge and has its entire edge gathered, is given the

proper shape and an opening provided in its smaller lower portion of the proper size for engagement with the head, it being understood that the hair is received and accommodated in the upper larger portion of the crown. 60

Secured by its inner edge to the gathered edge 2 of the crown is the continuous double flap member 3 which is formed of two pieces 65 of material having their right sides turned outwardly, said pieces forming the flaps being secured together at their opposite edges, as will be clearly understood by referring 70 to the drawings.

It will be understood that the inner edges of the two flap members are positioned upon opposite sides of the gathered edge 2 and the parts secured together by a row or rows of stitching 4. Positioned between the 75 outer edges of the continuous flap members is a strip of braid 5 which is secured in position by the row or rows of stitching 6 which serves to secure together the outer edges of the flap members. 80

The continuous flap 3 is formed by providing two strips of material each having a straight edge and a curved edge with the largest portion of the strip at the center of the same while the ends of said strip are 85 the narrow portions. Each strip has its ends connected and overlapped and secured together by stitching or any other suitable and well known means. The flap members are then reversed and placed one inwardly 90 of the other with their right faces or surfaces outwardly and the flap member then secured to the crown in the manner previously stated with the narrow portion of the double flap member indicating the front 95 of the cap when the same is used as a dust cap or morning cap and indicating the back of the device when the flap is to be turned downwardly to form the sun bonnet.

From the foregoing it will be seen that 100 I have provided a head gear of extremely simple construction and which may be readily converted into either a dust cap or sun bonnet and which when not in use, may be readily and neatly folded in compact form. 105 It will also be seen that as the flap 3 is constructed of two separate strips with their right sides outwardly, the right side or surface of the material only will show when the flap is in either position. It will also be 110 seen that the device may be constructed of various materials, either washable or non-

washable and will be extremely cheap to manufacture.

While I have shown the preferred embodiment of my invention, it will be understood that minor changes in the details of construction may be made within the scope of the appended claim without departing from the spirit of my invention.

Having thus described my invention, what I claim is:—

A three-piece combination cap and sun bonnet comprising a single crown member and a pair of opposed continuous flap members with their finished sides positioned out-

wardly whereby said flap may be turned 15 back against the crown to form a cap, said flap when in normal position serving as the extended portion of a sun bonnet, the inner edges of the flap members being secured to the opposite faces of the crown and around 20 the circular edge thereof.

In testimony whereof I hereunto affix my signature in the presence of two witnesses.

ELIZABETH ZIEGFELD.
